MACHINE FOR THE AUTOMATIC CLOSED RING JOINTING OF PLIABLE SHEETS

Pietro Molla, Magenta, Italy, assignor to S. A. F. F. A. S. p. A. Fabbriche Fiammiferi ed Affini, Milan, Italy

Application April 13, 1953, Serial No. 348,484

Claims priority, application Italy October 4, 1952

11 Claims. (Cl. 93—77)

Heretofore closed ring jointing of sheets of corrugated cardboard or other similar material for the manufacture of tubes for protective purposes for example, bottle packing etc. was generally done by means of an overlap type joint, the joint being secured by metal stitches or by application across the joint of strips of gummed paper.

The overlapped stitch joint has the disadvantage of localizing the strains and stresses placed upon it at the metal stitches and at the same time has little esthetic value due to the thickness of the overlapped edges. The overlapped gummed paper joint has the disadvantage of the weakness of the gummed paper, which in some cases is not easy to apply on materials which do not have smooth surfaces, such as the corrugated or double side corrugated paper.

It is an object of the present invention to provide new and improved automatic machines which produce closed ring type tubes or containers from sheets of corrugated or double side corrugated paper, smooth cardboard, thin sheets of wood or cellulose base material by the application of a natural or synthetic adhesive on the joined edges.

More particularly, the machine according to the claimed invention comprises a device for loading or feeding the sheet material to be worked, a device which effects the application of the adhesive on the edges of the sheets, a sheet folding device, a device for pressing the edges of the sheets when they have received the adhesive and an off-loading device for the finished product.

The product produced by these new and improved machines is a tube whose edges are butt jointed along a line parallel to its longitudinal axis and has the following advantages:

The line of the joint is very resistant to strain, especially if a synthetic adhesive of the correct type is used.

Any surface type material may be used and glued provided such material can be bent and is of sufficient thickness.

Uniformity of tube diameter with absence of jointing rib which appears when an overlap joint is made. This latter advantage is specially important when the tubes are made of a very elastic material such as double side corrugated paper. This double sided corrugated paper forms the subject matter of Italian Patent No. 471,165 in the name of Villoresi, which was filed on July 9, 1950, and is used for the protection of fragile cylindrical bodies such as bottles, tumblers, lamp bulbs and other similar glass objects.

In one embodiment of the present invention the automatic tube forming machine comprises the following parts:

1. A vertical loading hopper with adjustable sides so as to be adaptable to the various forms and sizes of sheet material to be glued into which the sheets are loaded by hand, in horizontal packs.

2. A continuous feed chain type conveyor on which are mounted small plates, the distances between which

2

can be adjusted to the sizes of the sheets in use, for extracting the sheets from the hopper and for carrying them the whole length of the machine.

3. An adhesive applying means comprising two units 5 adjustable for varying widths of sheet material one arranged on each side of the machine for applying liquid adhesive on the lateral edges of the sheets.

4. A pair of suitably shaped and adjustable guides, 10 which create a partial fold or bend on the lateral edges of the sheets around an electrically heated core. The guides are interchangeable so as to form tubes of varying size and shape.

5. A jointing unit made up of special adjustable guides which finish the fold around the core so as to butt together the edges which have received the adhesive. An electrically heated pressure bar is provided for exerting a pressure on the seal from above the joint line of the tube.

6. A rapid off-loading device placed at the end of the 20 feed chain conveyor ejects the finished tubes from the machine by throwing them into a collector bin. This ejection device may be used with a counter which registers the number of pieces made on the machine.

The invention will be described in detail, merely in an 25 exemplifying way and not in a limiting sense with reference to the following embodiments illustrated in the accompanying drawings, in which:

Fig. 1 is a schematic illustration, partially shown in 30 section, of an embodiment of the machine in an elevational view, showing the main parts above mentioned.

Fig. 2 is a plan view of the machine as shown in Fig. 1 in which the pressure bar and the relative supports are shown in dotted lines so as to show the guides more clearly which complete the ring closure of the tubes.

35 Fig. 3 is a schematic view in perspective of the formed platform placed at the outlet of the sheets from the hopper.

Fig. 4 is a schematic view in perspective of an adhesive 40 applying unit.

Fig. 5 shows a section of the machine through the line A—A' of Fig. 2.

Fig. 6 shows a section of the machine through the line B—B' of Fig. 1.

Fig. 7 shows in plan view the two continuous conveyor 45 chains of a modified form of the embodiment shown in Figs. 1, 2 and 6.

Fig. 8 shows a section through the line C—C' of Fig. 7.

Fig. 9 shows in elevation and partly in section, the hot 50 pressure unit according to a modified form of the embodiment shown in Figs. 1, 2 and 6.

Fig. 10 is a plan view of Fig. 9 in which in order to illustrate more clearly the subject of the modified form the entire pressure bar complex with its supports and gearing has been omitted.

Fig. 11 shows a section of a pressure bar support 55 through the line D—D' of Fig. 9.

Throughout this description reference will be made to the use of the particular double side corrugated paper 60 which is the subject matter of the above mentioned patent application. However, this does not limit in any way the general applications of such a machine according to the invention with other forms of pliable sheet material.

The sheets of double side corrugated paper, a previously 65 cut to size are inserted flat in the hopper 1 (Figs. 1 and 2), thus forming a pile or pack whose bottom sheet rests on the bed 9 in which is cut a longitudinal slot 10 for conveyor chain 2. So as to allow feed of variously sized sheets, the hopper 1 is fitted with guides 11 and 11' on 70 which are provided adjustable angle supports or brackets 12 and 12' forming part of the hopper. Guides 11, 11' provide adjustment as to length and width. The width of

the hopper is adjusted by fixing brackets 12, 12' by screws 14 and 14' arranged in slots 13, 13' formed in guides 11, 11'.

The feed of the sheets throughout the whole cycle of operations is effected by the chain conveyor 2, made up of links 15, on each of which it is possible to screw a plate 16 of a thickness suitable for the thickness of the double side corrugated paper used. By varying the distance of the plates 16 according to the length of the sheets, one obtains, with the movement of the chain conveyor 2, a feed having a uniform spacing of sheets. The paper sheets before leaving the hopper 1 through the opening 17 pass across a forming plate 18 (Fig. 3) which flattens the sheets and lightly presses the edges which receive the adhesive in such a way as to smooth out any small variations in the width of the sheets. The forming plate 18 is interchangeable so that the machine may be used for various sizes of sheets being worked.

The conveyor chain 2 engaging sprocket wheels 19 and 20 is driven by gear 20' and transmission chain 21. Gear 20' and chain 21 are directly coupled to a reduction motor unit.

The adhesive applying unit 3 includes two symmetrical apparatuses placed one on each side of the sheet as it arrives on the conveyor chain 2. Each apparatus (see Fig. 4) comprises an adhesive bath 22 or 22', into which dips a vertical revolving disc 23 or 23'. Discs 23, 23' carry away on their edges a small amount of adhesive and deposits a thin layer on the outside edges of the horizontal revolving discs 24 and 24'. Discs 24, 24' in turn apply the adhesive to the edges of the sheets with which they come into contact.

For simplicity the operation on only one side of the conveyor will be described.

The revolving vertical disc 23 is driven through a set of cylindrical gears 25, 26, 27, 28, shaft 29, sprocket 30, and the transmission chain 31 taking their motion from the sprocket 19 of the conveyor chain 2. The horizontal revolving disc 24 is driven through the shaft 32, the conical couple 33, the shaft 34 and the cylindrical gear 35 from the gear 26 already mentioned. Each adhesive applying apparatus is fitted to a base plate 36, which is able to slide within the guides 37 and 37'. Guides 37, 37' may be fixed in position by the screws 39 and 39', so as to provide an adjustment of the distances of the two adhesive applying units according to the widths of the paper sheets. Gear 28 is sliding on its own shaft 29 and has to be keyed into the position taken by the adhesive applying units.

The sheet, after passing between the adhesive applying discs 24 and 24' receives a slight bending of the lateral edges inside the guides 5 and 5', and round the parallel bars 44 and 44'. Bars 44, 44' are supported from back-lash by the arms 45 and 45' and are adjustable by means of the slots 46 and 46' so that they can close around the core leaving a ring type or annular space 4 arranged horizontally on the machine along the center line of the sheet and, under which the sheet itself runs.

The core 4 which is interchangeable according to the tube being made, is fixed at one end by the screws 40 and 40' of the support portion 41 (Figs. 1 and 2) and is free throughout all its length, which extends to the extreme end of the machine at the off loading end. The free part of the core 4 (Fig. 5) rests on the plates 16 which are fixed to the conveyor chain 2. Internally the core 4 is fitted with an electrical heating resistance 42 for drying the adhesive line on the internal portion of the tube. The folding of the edges of the sheet starts with the counter-action of the feed of the sheets against the guides 5 and 5' (see Figs. 1, 2 and 5), whose entry end with inclined plane and specially shaped faces inside cause the folding of the edges of the sheet against the core 4. The bars 44 and 44' serve to force the edges of the sheet to follow a predetermined course.

The guides 5 and 5' are interchangeable and adjustable

by means of the slots 43 and 43' and lock screws 38 and 38', thereby providing adjustment for the varying sheet sizes and to enable the guides to converge slightly towards the outlet thus rendering the bending of the edges of the sheets more gradual.

Upon reaching the downstream end of guides 5 and 5', the double sided corrugated sheet with its edges partially bent to tube form and with the edges of the sheets glued but not joined, is received in the guides 6 and 6'. Due to the shape of the internal faces of the guides 6, 6' being semi-circular and due to the pressing action of the sheets of the pressure bar 7, the bending action is completed so as to make the two glued edges of the sheet to come into contact. The guides 6 and 6' are interchangeable and the distances between them can be varied by means of the slots 47 and 47' and locking screws 48 and 48' thus allowing the production of a range of tube sizes as desired. So as to facilitate the entry under the pressure bar 7 of the sheets which are partially bent, especially when one is working on larger sizes whose glued edges might be too high, in the head of the pressure bar 7 is fitted an entry plate 49 which helps to complete the closure of the tube form itself. The pressure bar 7 (Fig. 6) formed by a rectangular section element 7' and by an element of channel section 50 with a sheet of insulator material in between 51, has a heater resistance 52 arranged inside it. This resistance 52, together with the resistance 42 of the core 4, serves to produce the necessary heat for the drying of the adhesive. The length of the guides 6 and 6' and the length of the pressure bar 7 is such as to allow the complete drying of the adhesive used which, as explained, can either be natural or synthetic. The pressure bar 7 is fixed to the bar carrier 53 by through bolts 54 and is carried by two elevation screws 55 and 55' (Fig. 1) by means of two bolted flanges 56 and 56'. The elevation screws 55 and 55' are carried on two supports 57 and 57' and are driven by a helical gear 58 (Fig. 6), which meshes on an endless thread 59 keyed to the shaft 60 which in turn is operated by a handwheel 61. The shaft 60 extends from the support 57 to the support 57' so as to give simultaneous action on both elevation screws 55 and 55'.

Having finished the hot pressure cycle after passing under the pressure bar 7 the tubes, which are evenly distanced apart, continue towards the off-loading point of the machine. The tubes are still on the core 4 and are pushed by the plates 16 of the conveyor chain 2. So as to avoid plate 16 damaging the tube end when the chain starts to pass under the bed 9 as it follows the curve of the sprocket 20, the machine is fitted with a knurled surface roller 8 which has a surface speed greater than that of the tube's motion. Roller 8 is placed at a convenient distance from the end of the travel of the chain conveyor 2 and is provided to move the tube forward quickly from the plate 16 before conveyor 2 starts to pass round the sprocket 20. Roller 8 throws the tube off the bed into a collector bin. The ejection wheel 8 (see Fig. 1) is driven through cylindrical gearing 62 and 63, from the cylindrical gear 64 which is keyed onto the shaft 65 of the sprocket 20. Between the ejection wheel 8 and the end of the conveyor 2 is placed a normal counter 66 which registers the number of tubes produced by the machine from a given time. The tube being pushed in the last section of the conveyor chain hits a lever 67 which operates the counter device 66. Lever 67 has time to return to the rest position before the next tube arrives.

A modified form of the machine according to the embodiment above described arises from the possibility of making movable the two fixed guides 6 and 6' so as to give maximum movement and feed to double corrugated sheets which happen to be very thin or of tubes which are so large that they offer large surfaces for frictional effect, or tubes made from materials which offer little resistance to the pressing effect of the plates 16 which

push the tubes on the conveyor chain 2. In Figs. 7 and 8 the guides 6 and 6' are replaced with a pair of endless chains 68 and 68', on whose links are fitted formed blocks 69 and 69'. These blocks are held against the bent edges of the sheet to maintain the tube closed during the hot pressure operation of the heated pressure bar 7. Because of the flexibility of the chains 68 and 68', they are made to slide within guides 71 and 71' which are fixed to the bed and are adjustable by means of the slots 72 and 72' and lock screws 73 and 73' to provide a means for lining up of the formed blocks 69 and 69'. The speed and direction of movement of the chains 68 and 68' are identical to the direction and speed of the conveyor chain 2. On the curved face of the blocks 69 and 69' it is possible to screw plates 70 and 70' (Fig. 8) which, similarly to the plates 16 on the conveyor chain 2, have the function of pushing the tubes on both sides, and like those, can be adjustably spaced in order to accommodate various tube lengths.

The chains 68 and 68' (Fig. 7) are meshed on pairs of sprockets 74 and 74' which are keyed to the shafts 75 and 75' carried by the supports 76 and 76'. One of the sprockets 74 and one of the sprockets 74' (Fig. 8) are driven through the respective shafts 75 and 75' on which are keyed the conical gears 77 and 77', by the shaft 78. Conical gears 79 and 79' are keyed to shaft 78 and are coupled with the conical gears 77 and 77' and the sprocket 80. Sprocket 80 is actuated by the main transmission.

The adjustment of the distance between the chains 68 and 68' is done by means of slots 80 and 81' in the base of the supports 76 and 76' and by lock screws 82 and 82' for fixing to the bed 9.

Another modified form tending further to facilitate the feed of the tubes when of material not adapted to the pushing action of the plates 17, 70 and 70' and which also eliminates friction against the pressure bar 7 and above all provides a means of automatic cleaning of the adhesive incrustations on the contact faces at the line of the tube joint comprises a continuous steel strip 83 (Figs. 9, 10 and 11) which turns around the pressure bar 7 and bar carrier 53 assembly so that it comes into contact with the tubes. The strip steel can be easily cleaned of adhesive deposits by means of a scraper 84 mounted on the arms 85 and 85' or with some other similar means such as a sponge wiper or other suitable device.

In carrying out this modified form of the invention the pressure bar 7 which was described as being suspended by the flange 56 fixed on the upper part of the bar carrier block 53 as shown in Fig. 6, is supported by means of bracket 86 which is secured horizontally to the flange 56 and laterally to the bar carrier block as is shown in Fig. 11, with a consequent back placing of the bar holder arm supports 57 and 57' on the bed 9 (Fig. 9).

The steel strip 83 (Fig. 10) is carried on two pulleys 87 and 87' which are mounted respectively on the shafts 88 and 88', which in their turn are mounted on supports 89 and 89'. To the latter are fixed the elevation screws 90 and 90' (Fig. 9) on which are screwed the cylindrical nuts 91 and 91' which rest on the supports 92 and 92'. By using the nuts 91 and 91' it is possible to adjust the height of the strip 83 against the work level. The supports 92 and 92' (Fig. 10) are fixed to the bed by means of fixing screws 93 and 93' and by slots 94 and 94' which allow the adjustment for tension on the strip 83.

The steel strip 83 is driven by the pulley 87' on whose shaft is keyed a sprocket 95 which in turn is driven by the chain 96 (Fig. 9). Chain 96 sliding on the guide gear 97 and on the tensioner 98, is actuated by the gear 99. Gear 99 is keyed on a shaft 100 which carries the cylindrical gear 101. Gear 101 is actuated by cylindrical gear 64 which is shown as that driving the knurled roller 8 which effects the ejection of the tubes.

The transmission chain 96, so as to be able to adapt itself to the adjustments in height of the steel strip 83, 75

has been fitted with a tensioner device made up of a lever 102 pivoted on the support 103 and carrying on one end of the arm, the tensioner 98, while the other end of the arm is fixed to the return spring 104 which is anchored to the bed 9.

The provision of the steel strip 83, obviously eliminates the need for the entry plate 49 applied to the head of the pressure bar 7 (Fig. 1).

I claim:

- 10 1. A machine for forming tubes from sheets of pliable material comprising means for advancing spaced sheets of said material, means for applying an adhesive to two substantially parallel edges of each of said sheets of material, means for bending said sheets of material into tubular forms and disposing said substantially parallel edges of each of said tubular forms in abutting relationship to form tubes having butt seams, and means for applying heat and pressure to the inner and outer surfaces of each seam of each tube to dry the adhesive.
- 20 2. A machine for forming tubes from sheets of pliable material comprising a conveyor means for advancing spaced sheets of said material through the machine, means for applying a liquid adhesive to two substantially parallel edges of each of said sheets of material, means for bending each of said sheets of material into tubular forms comprising a core arranged above said sheets of material and arcuate guiding means arranged around said core, said guiding means presenting concave surfaces toward said core, said conveyor means moving said sheets of material within said guiding means and said concave surfaces of said guiding means forming said sheets of material to dispose said substantially parallel edges of each of said sheets of material in abutting relationship to form tubes having butt seams, and means arranged adjacent said seams of each of said tubes for forcing said seams of said tubes against said core.
- 30 3. A machine for forming tubes from sheets of pliable material comprising a hopper for stacking a plurality of flat sheets of pliable material, a conveyor comprising spaced plates for extracting one sheet at a time from said hopper and pushing it through said machine, means for actuating said conveyor, means for applying a liquid adhesive to two opposite edges of each of said sheets of material, means for bending each of said sheets of material into tubular forms comprising a heated core arranged above said sheets of material during part of their actuation through said machine and arcuate guiding means arranged around said core, said guiding means presenting concave surfaces toward said core, said conveyor moving said spaced sheets of material within said guiding means and said concave surfaces of said guiding means forming said sheets of material to dispose said opposite edges of each of said sheets of material in abutting relationship to form tubes having butt seams, and sealing means arranged adjacent the seams of said tubes for forcing said seams of said tubes against said core to dry the adhesive.
- 40 4. The combination set forth in claim 3 in further combination with an outfeed roller for rapidly ejecting the finished tubes from said conveyor to a retainer bin.
- 50 5. A machine for forming tubes from sheets of pliable material comprising a hopper for stacking a plurality of flat sheets of pliable material, an endless chain conveyor comprising spaced plates secured to the links of said chain for extracting one sheet at a time from said hopper and pushing it through said machine, means for actuating said conveyor, means comprising a plurality of discs in frictional engagement with said material for applying a liquid adhesive to two opposite edges of each of said sheets of material, means for bending each of said sheets of material into tubular forms comprising a heated core arranged above said sheets of material during part of their actuation through said machine and arcuate guiding means arranged around said core, said guiding means presenting concave surfaces toward said core, said conveyor moving said spaced sheets of material within said guiding
- 60 65
- 70

means and said concave surfaces of said guiding means forming said sheets of material to dispose said opposite edges of each of said sheets of material in abutting relationship to form tubes having butt seams, and sealing means comprising a heated bar arranged adjacent the seams of said tubes as said tubes are actuated through said machine for actuating the seams of said tubes against said core to dry the adhesive.

6. The combination set forth in claim 5 in further combination with horizontally spaced conveyor means positioned to engage the sides of the tubular formed sheets of material for the propulsion thereof through said machine.

7. A machine for forming tubes from sheets of pliable material comprising a hopper having a plurality of walls spaced a predetermined distance apart for stacking a plurality of flat sheets of pliable material, a conveyor comprising spaced plates for extracting one sheet at a time from said hopper and pushing it through said machine, means for actuating said conveyor, means for applying a liquid adhesive to two opposite edges of each of said sheets of material, means extending along the longitudinal axis of said machine for bending each of said sheets of material into tubular forms comprising a first pair of arcuate guiding means having concave surfaces of a predetermined curvature facing each other, a second pair of arcuate guiding means having concave surfaces of a second predetermined curvature facing each other and a heated core arranged within said guiding means along the longitudinal axis of said machine, said core being arranged above said sheets of material as said material moves through said machine, said conveyor moving said spaced sheets of material within said guiding means and said concave surfaces of said first guiding means forming said material into semi-circular forms and said concave surfaces of said second guiding means forming said semi-circular forms to dispose said opposite edges of said forms in abutting relationship to form tubes having butt seams, and sealing means arranged adjacent the seams of said tubes for forcing the seams of said tubes against said core to dry the adhesive.

8. The combination set forth in claim 7 in further combination with means for moving said spaced walls a second predetermined distance apart to accommodate another size sheet of material.

9. A machine for forming tubes from sheets of pliable material comprising a hopper for stacking a plurality of flat sheets of pliable material, a conveyor comprising spaced plates for extracting one sheet at a time from said hopper, means for actuating said conveyor longitudinally through said machine, means comprising a detachable forming plate arranged below said hopper but above said conveyor for removing the wrinkles from said sheets of material to uniform their widths, means comprising a plurality of discs arranged on opposite edges of said sheets of material which are arranged along the longitudinal axis of said machine for applying a liquid adhesive to said edges of each of said sheets of material, means extending along the longitudinal axis of said machine for bending each of said sheets of material into

tubular forms comprising a first pair of arcuate guiding means having concave surfaces of a predetermined curvature facing each other, a second pair of arcuate guiding means having concave surfaces of a second predetermined curvature facing each other, a heated core arranged within said guiding means above said sheets of material as said material moves longitudinally through said machine, and guiding bars arranged within said guiding means to cooperate with said concave surfaces of said first and second guiding means to form said sheets of material, said conveyor moving said spaced sheets of material within said guiding means and said concave surfaces of said first guiding means forming said material into semi-circular forms on said concave surfaces of said second guiding means forming said semi-circular forms to dispose said opposite edges of said forms in abutting relationship to form tubes having butt seams, and sealing means arranged adjacent the seams of said tubes for forcing the seams of said tubes against said core to dry the adhesive.

10. A machine for forming tubes from sheets of pliable material comprising a hopper for stacking a plurality of flat sheets of pliable material, a conveyor comprising spaced plates for extracting one sheet at a time from said hopper and pushing it longitudinally through said machine, means for actuating said conveyor, means for applying a liquid adhesive to two opposite edges of each of said sheets of material, means for bending each of said sheets of material into tubular forms comprising a heated core arranged above said sheets of material and arcuate guiding means arranged around said core, said guiding means presenting concave surfaces toward said core, said conveyor moving said spaced sheets of material within said guiding means and said concave surfaces of said guiding means forming said sheets of material to dispose said opposite edges of each of said sheets of material abutting relationship to form tubes having butt seams, sealing means comprising a heated bar arranged adjacent the seams of said tubes as said tubes are actuated through said machine for forcing the seams of said tubes against said core to dry the adhesive, and means for removing the excessive adhesive from said tubes comprising a revolving metallic strip provided to pass between said pressure bar and said tubes.

11. The combination set forth in claim 10 in further combination with a scraping means for cleaning the adhesive from said strip.
